CLAIM

The ornamental design for a tricycle with reclining seat, as shown and described.

DESCRIPTION

The nature and intended use of the article in which the design is embodied is that of a tricycle with a reclining seat for children and the like.

FIG. 1 is a perspective view of a tricycle with a reclining seat showing my new design;

FIG. 2 is a bottom view thereof, shown with the canopy removed for the ease of illustration;

FIG. 3 is a side view thereof;

FIG. 4 is a front view thereof;

FIG. 5 is a rear view thereof; and,

FIG. 6 is a top view thereof, shown with the canopy removed for the ease of illustration.

1 Claim, 6 Drawing Sheets
